[57] CLAIM

The ornamental design for a disk drive, as shown and described.

DESCRIPTION

FIG. 1 is a top, front right side perspective view of a disk drive showing my new design;

FIG. 2 is a top plan view thereof on an enlarged scale;

FIG. 3 is a bottom plan view thereof on an enlarged scale;

FIG. 4 is a front elevational view thereof on an enlarged scale;

FIG. 5 is a rear elevational view thereof on an enlarged scale;

FIG. 6 is a left side elevational view thereof on an enlarged scale;

FIG. 7 is a right side elevational view thereof on an enlarged scale;

FIG. 8 is a cross sectional view thereof as taken along line 8—8 of FIG. 4.
